CLAIM

The ornamental design for a gear for wave gear drive, as shown and described.

DESCRIPTION

FIG. 1 is a top view of a gear for wave gear drive, showing my new design;

FIG. 2 is a bottom view thereof;

FIG. 3 is a side view thereof; and,

FIG. 4 is a cross-sectional view thereof.

The gear for wave gear drive is axially symmetrical. Accordingly, all side views thereof are substantially the same.
